UNITED STATES PATENT OFFICE.

CHARLES P. TOPLIFF, OF TACOMA, WASHINGTON.

SHOE-FASTENER.

No. 922,976.

Specification of Letters Patent. Patented May 25, 1909.

Application filed February 14, 1908. Serial No. 415,958.

To all whom it may concern:

Be it known that I, CHARLES P. TOPLIFF, a citizen of the United States, residing at Tacoma, county of Pierce, and State of Washington, have invented certain new and useful Improvements in Shoe-Fasteners, of which the following is a specification.

My invention relates to shoe fasteners.

The present invention relates to that class of shoe fasteners embodying hooks or members on the respective sides or edges of the front opening of the shoe, and a tongue carrying clasps which are adapted to be simultaneously slid into engagement with or detached from the hooks or members on the shoe and it has for its object the provision of an improved and novel fastener of this character which will be of neat appearance, simple and durable construction, afford a properly tight and secure closure for the opening in the shoe and enable the shoe to be fastened or unfastened with great facility.

The present invention aims to provide a device of the character set forth which will possess none of the defects of earlier devices of this character and with that end in view it provides a fastener which conforms to the shape of the foot, instead of forming a conspicuously bulging or protruding ridge which has heretofore been a common defect of such fasteners; provides simple and effective means for holding the fastening tongue in position; and affords a secure fastening of neat and dressy appearance, enabling the invention to be used on ladies' shoes as well as gentlemen's foot wear.

Having the foregoing objects in view, the invention consists of those features of construction and combinations and adaptations 40 of parts set forth fully hereinafter. The novel features of the invention being recited in the appended claims.

In the accompanying drawings:—Figure 1 is a perspective view of a ladies' shoe provided with the invention, the fastening tongue being shown with surface ornamentation; Fig. 2, an enlarged detail view showing the hooks on the adjacent edges of the shoe flaps; Fig. 3, a rear view of the tongue and articulated clasps carried thereby which are adapted to engage the hooks shown in Figs. 2, 5, and 11 or the studs shown in Figs. 4, 8, 9, and 10. Fig. 4, a horizontal section through one of the clasps of Fig. 3, engaged with the hooks of Figs. 8, 9, or 10. Fig. 5, a

view of the metal blank from which the continuous strips of hooks shown in Fig. 2 are formed; Fig. 6, a horizontal section showing the retainer for holding the tongue in position on the shoe; Fig. 7, a detail of one of the clasps; Fig. 8, a view like Fig. 2 but showing lacing studs or hooks; Fig. 9, a view like Fig. 4 but showing the lacing studs or hooks of Figs. 8 and 10 in full lines; Fig. 10, a detail of one of the lacing studs or hooks; and Fig. 11, a detail of a hook which can be used in place of the continuous strip of hooks shown in Fig. 2 or the lacing studs or hooks of Figs. 8, 9, and 10.

The invention is shown in connection with a ladies' shoe 1 but it is adapted to any foot wear. The shoe 1 has flaps 2 whose edges 3 are separated a short distance so that in the operation of lacing or fastening the shoe 75 these edges may be drawn toward each other to cause the shoe upper to properly conform to the foot.

Referring to Figs. 2 and 5, from a metal blank (Fig. 5) hooks are cut and rebent over 80 the body 4, thereby providing the continuous, yet bendable, strips of hooks shown in Fig. 2 which are secured to the flaps 2 adjacent the edges 3 in any suitable or well known manner.

Instead of using a continuous strip of hooks, a series of lacing hooks or studs 6 shown in Figs. 8 and 10 may be employed or a plurality of hooks 7 such as shown in Fig. 11 may be used.

There is provided a leather tongue 8 whose outer surface may be provided with any suitable ornamentation 9, if desired, said tongue having, by preference, a finger piece 10 at its upper end to facilitate its manipulation. The tongue 8 has secured to its back a sufficient number of metal clasps such as shown in Fig. 7, to suitably engage the hooks 5. The clasps, which are shown at 11, have a relatively flat body 12, curved 100 parts 13, straight rebent parts 14, and lips 15 which lie substantially parallel to the body part 12. The rebent parts 14 are secured, preferably by rivets 16 passing through holes 17, to the tongue 8, the respective clasps 11 being positioned on the tongue with their edges located closely adjacent, thereby providing an articulated structure which is adapted to bend at every point to conform itself to the curvature of 110

the front of the foot. By preference the lowermost clasp 11 has an extension 18 which is secured by rivets 19 to the tongue 8 so that the lower open part of the shoe is 5 closed and air and water prevented from having access to the interior of the shoe thereat. The tongue carries on its upper end a metallic fastening section 20 secured by rivets 20^a and has a free part provided with 10 a key hole slot 21 adapted to engage a stud 22 on the upper part of the shoe whereby the tongue is locked against rising or falling but may be readily detached and removed.

Assuming that the tongue and articulated 15 clasp is detached, the user grasps the finger piece 10 and slips the uppermost clasp 11 over the lowermost hooks 5, then pulling the tongue upwardly, in doing which the lips 15 of the clasps successively slide under 20 and pass the hooks 5 as the tongue ascends until the tongue has been positioned, when it may be secured by the parts 21 and 22 and in such movement the edges 3 are drawn more or less together and a snug closing of 25 the shoe opening is obtained.

The free edge of the leather tongue 8 which constitutes a margin beyond the outer edges of the clasps 11 articulated on said tongue, together with the angle of the re- 30 bent parts 14 of the clasps causes the fastener to form a close inconspicuous joint with the flaps 2 of the shoe upper and on account of the general construction of the clasps and hooks, the fastener is a neat and 35 unobtrusive one, devoid of any objectionable bulged or rigid appearance, thus overcoming a serious defect of earlier fastening devices of this general character.

Having thus described my invention, what 40 I claim as new and desire to secure by Letters Patent, is:—

1. In a shoe fastener, the combination with engaging members on the flaps of the shoe upper, of a tongue carrying a plurality 45 of clasps composed of a body covered only on its outer faces by the tongue and having

flat thin lips adapted to engage the engaging members aforesaid.

2. In a shoe fastener, the combination with engaging members on the flaps of the 50 shoe upper, of a tongue carrying a plurality of clasps composed of a body having flattened rebent parts provided with lips which are adapted to engage the engaging members aforesaid, the said body and rebent portions 55 being covered on their outer faces only by said tongue, and the lips having no covering.

3. In a shoe fastener, the combination with engaging members on the flaps of the shoe upper, of a tongue carrying a plurality 60 of clasps composed of a body having flattened rebent parts disposed angularly to said body and terminating in lips which point toward each other and are disposed substantially parallel to the body and adapted to 65 engage the engaging members aforesaid.

4. In a shoe fastener, the combination with the flaps of the shoe upper, of engaging members carried by said flaps, a flexible tongue, a plurality of clasps carried by 70 said tongue, edge to edge and providing an articulated structure, said clasps being composed of a relatively flat body having wings extending outwardly and angularly therefrom and free lips which are. 75 disposed substantially parallel thereto and adapted to engage the engaging members.

5. In a shoe fastener, the combination with the flaps of the shoe upper, of engaging devices carried thereby, a flexible tongue, 80 and a plurality of clasps carried by the tongue and adapted to engage the engaging devices aforesaid, said tongue having a free margin extending laterally beyond the ends of the clasps adapted to conform to the shoe 85 and constitute a joint therewith.

In testimony whereof, I hereunto affix my signature in presence of two witnesses.

CHARLES P. TOPLIFF.
